UNITED STATES PATENT OFFICE.

OSCAR L. SCALBOM, OF CHICAGO, ILLINOIS.

SIGNAL.

1,268,162.

Specification of Letters Patent. Patented June 4, 1918.

Application filed February 2, 1917. Serial No. 146,052.

To all whom it may concern:

Be it known that I, OSCAR L. SCALBOM, a citizen of the United States, residing at Chicago, in the county of Cook and State of Illinois, have invented certain new and useful Improvements in Signals, of which the following is a specification.

This invention relates to improvements in signals, particularly adapted though not necessarily limited in its use with flash lights, and one of the objects of the invention is to provide an improved device of this character, by means of which different signals may be instantly changed as the occasion may require.

A further object is to provide an improved device of this character which may be readily attached to a flash light to cooperate with the light to produce the desired signal, and which may as readily be detached therefrom.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention and in which:

Figure 1 is a side elevation of a flash light having an attachment applied thereto constructed in accordance with the principles of this invention.

Fig. 2 is a right hand end elevation of the parts shown in Fig. 1.

Fig. 3 is a sectional view as taken on line 3—3, Fig. 2.

Fig. 4 is a bottom plan view of the parts shown in Fig. 3.

Referring more particularly to the drawing, the numeral 10 designates an ordinary flash light provided with a lens casing 11 at one end thereof, and in which casing the lens is arranged.

The signal attachment which is adapted to be removably applied to the flash light, comprises a body portion 12 which may be constructed of any suitable material, and is of a form and configuration to conform to the contour of the lens. This body is preferably of a size slightly larger than the lens casing 11 and is provided with spring fingers or projections 13 adapted to engage over the

edge of the lens and casing to hold the same 55 secured to the lens.

The body 12 is provided with a series of openings 14 of any desired size and configuration and arranged in any suitable manner with respect to each other but are in a position with respect to the lens so that when the openings 14 are uncovered, the light will be exposed therethrough. The remaining portion of the body 12 is preferably of a construction as to prevent the light from being visible except through the openings 14 when the latter are uncovered. A disk 15 is rotatably connected with the body 12 in any suitable manner such as by means of a pivot 16, and a portion of the periphery of 70 the disk is preferably cut away as at 17 to any desired extent around the periphery, so that any one or more of the openings 14 may be uncovered by the cutaway portion of the disk when the latter is properly positioned with respect thereto.

The disk is provided with an operating handle 18 adapted to project through a suitable slot 19 in the body 12, so that by the movement of the handle 18, the cutaway 80 portion 17 of the periphery of the disk may be moved so as to uncover any one or more of the openings 14.

In order to assist the operator in positioning the disk 15 with respect to the openings 14, and to hold the disk when thus adjusted, any suitable temporary locking means may be provided, such for instance as a projection on one of the parts and spaced recesses on the other parts to receive the projection.

In the present form of the invention a projection 20 is shown on the disk 15 and spaced recesses 21 are shown on the body 12 adapted to receive the projection. The natural spring of the parts with respect to each other will be sufficient to permit the parts to yield so that the projection 20 may be moved out of one recess 21 and into the next recess.

This invention is particularly advantageous for use in theaters or halls or other places, where it is desired to seat people, as the usher at one end of the aisle can signal to another person at another point in the house and indicate the number of vacant 105 seats, without necessitating a trip of the usher to the entrance each time vacant seats are found at different points in the house.

All that is necessary for the usher is to move the disk 15 so that a number of openings 14 will be exposed to permit the light to shine therethrough according to the number of vacant seats.

Obviously this device is well adapted for many other uses and is also adapted to be constructed in many other forms without departing from the spirit of this invention.

10. What is claimed as new is:

1. In combination, a flash light embodying a light opening, a signal device arranged to extend across said opening, and spring fingers connected with the signal and adapted to removably and frictionally secure the signal in position, said signal device embodying means whereby the signal may be varied at will.

2. In combination, a flash light embodying a light opening, a signal device of a size slightly larger than the said opening, and yielding clamping means removably securing the signal in position, said signal device embodying means whereby the signal may be changed at will.

3. As an article of manufacture, a signal attachment for flash lights and the like, said signal embodying coöperating and relatively movable elements adapted to be arranged within the field of light, means for imparting such relative movement to the elements for causing different signals to be given by the light, and means connected with the signal and adapted to clamp the frame of the light opening of the flash light for securing the said attachment in position for free removal.

4. A signal attachment for flash lights and the like, embodying coöperating and relatively movable elements arranged within the field of light, one of said elements having a series of openings, and means for imparting such relative movement to the elements for causing the other of the said elements to successively close the said openings at will.

5. A signal attachment for flash lights and the like, embodying coöperating and relatively movable elements arranged within the field of light, one of said elements embodying a plurality of openings, means for imparting such relative movement to the elements for causing the said openings to be successively closed or opened, and means for removably attaching said signal in front of the light.

6. A signal attachment for flash lights and the like, embodying coöperating and relatively movable elements arranged within the field of light, means for imparting such relative movement to the elements for caus-

ing different signals to be given by the light, and means embodying spring fingers adapted to removably engage the frame of the light opening for securing the signal in 65 position.

7. In combination, a flash light embodying a lens, a signal device arranged adjacent the lens, and means for detachably securing the signal device to the frame of 70 the lens, the said signal device embodying a body having one or more openings therein and through which the light rays pass, and a shutter adjustably connected with the body and adapted to be moved to open or 75 close one or more of the said openings.

8. In combination, a flash light embodying a lens, a signal device arranged adjacent the lens, and means for detachably securing the signal device to the frame of the 80 lens, the said signal device embodying a body having one or more openings therein and through which the light rays pass, and a shutter movably connected with the body and adapted to be moved to open or close 85 one or more of the said openings, and interengaging means between the shutter and body for releasably securing the shutter in its adjusted position with respect to the body.

9. In combination, a flash light embodying a lens, a signal device arranged adjacent the lens, and means for detachably securing the signal device in front of the lens, the said signal device embodying a body 95 having one or more openings therein and through which the light rays pass, and a shutter movably connected with the body and adapted to be moved to open or close one or more of the said openings, said body 100 having a spring portion extending over the periphery of the lens for detachably securing the signal in position.

10. A signal attachment for flash lights and the like embodying coöperating relatively 105 movable elements arranged within the field of light, one of said elements having an opening and the other element being adapted to be moved across said opening to close and open the same, and spring portions connected with one of the elements and adapted to be sprung over the wall of the light opening for securing the said attachment in position for free removal at will.

In testimony whereof I have signed my 115 name to this specification, in the presence of two subscribing witnesses, on this 31st day of January, A. D. 1917.

O. L. SCALBOM.
